UNITED STATES PATENT OFFICE.

EDWARD T. WHEED, OF CHICAGO, ILLINOIS.

PLATE-HOLDER FOR PRINTING-PLATES.

SPECIFICATION forming part of Letters Patent No. 516,672, dated March 20, 1894.

Application filed July 5, 1893. Serial No. 479,594. (No model.)

To all whom it may concern:

Be it known that I, EDWARD T. WHEED, a citizen of the United States, residing at Chicago, in the county of Cook and State of Illinois, have invented certain new and useful Improvements in Plate-Holders for Printing Purposes; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to the base or holder for mounting electrotype and stereotype plates for the printing press.

Its objects are to provide a sectional holder, all or a part of which may be used according to 20 the size of the plate; to facilitate the adjustment of the several plates upon the form; and to provide an improved clamping block.

The invention consists of a central block which may be used alone for carrying a small 25 plate, and a succession of right-angled strips for enlarging the area of the holder to accommodate larger plates.

It consists further in the formation of these 30 parts so that clamping blocks for securing the plates may be adjusted upon them.

It consists of such further parts and in the arrangement of the various parts as herein-after set forth.

In the accompanying drawings are shown 35 in Figure 1. a plan of the plate holder adjusted to carry a plate of large size; Fig. 2, a plan view of the central block carrying a plate and locked in a chase; Fig. 3, a bottom plan view of the central block; Fig. 4, a transverse 40 vertical section on the line 4—4 of Fig. 2; Fig. 5, an elevation of the ordinary locking rack in engagement with the pinion of a clamp; Fig. 6, a side elevation of one of the clamping blocks; Fig. 7, a plan of one of the outer 45 angular sections; Fig. 8, a transverse vertical section on the line 8—8 of Fig. 7; Fig. 9, two of the outer angular sectional pieces of different holders in proximity.

The common practice has been to use a 50 separate block for each plate and consequently blocks of various sizes of plates.

The basic elements of my holder are the oblong rectangular central blocks 1, 2, each of which is adapted to hold a small plate, 23, as shown in Fig. 2, and to be locked in a chase 55 24, alone if but one page is to be printed. The plate 23 is locked to the holder by means of the keyed clamp blocks 21, whose stems fit within the holes 16, 16, and the screw adjusted clamping blocks 17, which are fitted within the 60 slots 14, 14, entering from the side of the block. The bosses 11, 11, upon the block 1, and 12, 12 upon the block 2 are for the purpose of enlarging the area of these blocks to accommodate plates which would overlap them, each boss 65 having a key hole so as to carry a clamping block 21. The adjacent blocks in that event are separated by the use of "furniture" to provide the proper margins for the pages. It will be seen that the blocks 1, 2 are adapted to fit 70 together, side to side or end to end and that a four page sheet can be printed by the use of two each, arranged as indicated in Fig. 1, so that in printing small pages it is only necessary to re-duplicate the blocks 1, 2, to provide one 75 for each page. Should the plates be too large for the central blocks the size of the holder is increased by placing against the block 1, the right-angled strip 3, and against the block 2, the right-angled strip 4. The clamping 80 blocks 17, will now be placed in the slots 13^a, 14^a, and one of the key blocks 21, may be placed in each of the adjacent ends of the strips 3, 4. The holder may be still further enlarged by the addition of the angular strips 85 5, 6, 7, 8, 9, 10, as may be required—the clamping blocks 17 being always placed in the outer edge of the holder, and the blocks 21 opposite to them in the holes 15, 16. These holes are numerous and variously located so as to admit of considerable range in the location of 90 the plate upon the holder.

In printing from more than four plates the arrangement of the four holders shown in Fig. 1, is repeated, the outer edges coming together in the manner indicated in Fig. 9.

It will be observed that the slots 13, 13^a, 13^b, &c., in the block 1, and strips co-operating with it are in relatively different positions from the slots 14, 14^a, 14^b, &c., in block 2 and the 100 strips co-operating with it so that when the outer edges of the even numbered blocks or

strips lie against the outer edge of the odd numbered blocks or strips their respective slots do not coincide.

The castings may be solid. There is however no necessity for using so much metal and the bottoms of the blocks and strips are preferably chambered, or, differently described.

The platform of the plate holder is supported upon flanges and ribs 22, 22^a.

10 The clamping blocks 17, 21, are formed with beveled edges to engage the plates, whose sides are commonly of similar form. The key stem 21^a of the clamping blocks 21, is provided with a bit and the holes 15, 16, are 15 each provided with a lateral slot to permit its entry. The stem having been inserted in the hole and the block being turned upon it a quarter turn is securely locked in place.

10 The clamping blocks 17 are each provided 20 with a shank adapted to project within the slots 13, 14, &c., and having shoulders for engaging the under surface of the holder platform. The shank is also provided with a screw threaded aperture within which is 25 placed a screw threaded shaft or bolt 18, carrying at its outer end a pinion 19. A journal block 20, is also mounted upon the outer end of the bolt 18. These journal blocks are oblong rectangular in shape and are slotted at 30 one end so as to inclose the pinion, which however, extends somewhat above the block. The solid end of the block serves as furniture in making up the form and relieves the pinion from pressure so that it may be freely 35 turned by means of the hand rack bar 25.

35 The blocks 20 may be thrown over in either direction as the clamp is adjusted to its place so that when two parts as 3, 4, of the holder are brought together as shown in Fig. 9, those 40 upon the one piece do not interfere with those upon the other and the parts of the holder are separated only by the thickness of one of the journal blocks. This adjustment is made possible by the relative location of the slots 45 13, 14, &c., as herein before described.

50 The angular strips 5, 6, 7, 8, are shown as having more slots upon their longer sides than the other strips. This construction is to adapt the holder to the peculiar form of the plates used in legal printing, which are of such size as to require the use of these strips and in which marginal notes are common and the edges of the plates are consequently irregular.

55 I claim as my invention—

1. In a printing plate holder the combination with the central blocks 1, 2, adapted to lie against each other side to side or end to end, of right angled extension strips 3, 4, each adapted to lie along two sides of one of the central blocks, said blocks having a series of holes through their faces adjacent to two sides, and said strips having similar holes near their ends and slots entering from their outer edges and extending partially 60 across their faces, clamping blocks 21, having stems for fitting within the holes, and clamping blocks 17, adapted to slide in the slots in the strips 3, 4, and screw threaded bolts for adjusting said blocks 17, substantially as described and for the purpose specified.

2. In a printing plate holder the combination with central oblong, rectangular blocks 1, 2, adapted to lie side to side or end to end, of right angled extension strips of increasing length for increasing the face area of the plate holder without changing its form, said central blocks having holes in their faces near their adjacent sides for receiving the 75 stems of clamping blocks, and said strips having transverse slots entering from their outer edges and extending a portion of the distance across their faces for carrying adjustable clamping blocks, said slots in the 80 strips co-operating with the block 1, being in different position relatively to the slots in the strips co-operating with the block 2, substantially as described and for the purpose specified.

3. The combination with printing plate holders having slots entering from their outer edges and extending partially across their faces, of clamping blocks adapted to slide within said slots, screw threaded adjusting 95 bolts fitting within the bases of said blocks, a pinion fixed upon the outer end of each of said bolts, a journal block mounted upon each bolt and having a slot within which said pinion is located, said block having a solid portion extending in one direction only from the bolt, substantially as described and for the purpose specified.

In testimony whereof I affix my signature in presence of two witnesses.

EDWARD T. WHEED.
